US0D1110962S

(12) **United States Design Patent** (10) **Patent No.:** **US D1,110,962 S**
(45) **Date of Patent:** **** Feb. 3, 2026**

(54) **ELECTRICAL CONNECTOR**

(71) Applicant: **Samtec, Inc.**, New Albany, IN (US)

(72) Inventors: **James Edward Borgelt**, Jeffersonville, IN (US); **Doug Edward McCartin**, Henryville, IN (US)

(73) Assignee: **Samtec, Inc.**, New Albany, IN (US)

(**) Term: **15 Years**

(21) Appl. No.: **29/905,474**

(22) Filed: **Oct. 20, 2023**

(51) **LOC (15) Cl.** 13-03

(52) **U.S. Cl.**

(57) **CLAIM**

The ornamental design for an electrical connector as shown and described.

DESCRIPTION

FIG. 1 is a front, top, and left side perspective view of an electrical connector of one design of an electrical connector; FIG. 2 is a front, top, and right side perspective view of the design of FIG. 1;

FIG. 3 is a front, bottom, and right side perspective view of the design of FIG. 1;

FIG. 4 is a front, bottom, and left side perspective view of the design of FIG. 1;

FIG. 5 is a back, top, and left side perspective view of the design of FIG. 1;

FIG. 6 is a back, bottom, and right side perspective view of the design of FIG. 1;

FIG. 7 is a front view of the design of FIG. 1;

FIG. 8 is a back view of the design of FIG. 1;

FIG. 9 is a left side view of the design of FIG. 1;

FIG. 10 is a right side view of the design of FIG. 1;

FIG. 11 is a top view of the design of FIG. 1; and,

FIG. 12 is a bottom view of the design of FIG. 1.

The dash-dot broken lines of the figure drawings are included to show the boundaries of the claimed design. The dash-dot broken lines form no part of the claimed design.

The dash-dot broken lines in the figures illustrate portions of the electrical connector that form no part of the claimed design.

1 Claim, 12 Drawing Sheets
